UNITED STATES PATENT OFFICE

168,807

SELF-PROPELLED TOY BOAT

Harold H. Reuther, Wyomissing, Pa.

Application April 17, 1951, Serial No. 14,873

Term of patent 3½ years

(Cl. D34—15)

To all whom it may concern:

Be it known that I, Harold H. Reuther, a citizen of the United States of America, residing at 1157 Cleveland Avenue, Wyomissing, in the county of Berks and Commonwealth of Pennsylvania, have invented a new, original, and ornamental Design for a Self-Propelled Toy Boat, of which the following is a specification, reference being had to the accompanying drawings, forming part thereof.

Figure 1 is a front perspective view of a self-propelled toy boat in accordance with my invention.

Fig. 2 is a rear perspective view of the same.

The essential features of my design are shown in full lines.

I claim:

The ornamental design for a self-propelled toy boat, as shown and described.

HAROLD H. REUTHER.
